(57) **CLAIM**

The ornamental design for a therapeutic pneumatic support stocking, as shown and described.

DESCRIPTION

FIG. 1 is a perspective view of a first embodiment of a therapeutic pneumatic support stocking.

FIG. 2 is a right side view of the therapeutic pneumatic support stocking of FIG. 1.

FIG. 3 is a left side view of the therapeutic pneumatic support stocking of FIG. 1.

FIG. 4 is a front view of the therapeutic pneumatic support stocking of FIG. 1.

FIG. 5 is a rear view of the therapeutic pneumatic support stocking of FIG. 1.

FIG. 6 is a top view of the therapeutic pneumatic support stocking of FIG. 1.

FIG. 7 is a bottom view of the therapeutic pneumatic support stocking of FIG. 1.

FIG. 8 is a perspective view of a second embodiment of a therapeutic pneumatic support stocking.

FIG. 9 is a right side view of the therapeutic pneumatic support stocking of FIG. 8.

FIG. 10 is a left side view of the therapeutic pneumatic support stocking of FIG. 8.

FIG. 11 is a front view of the therapeutic pneumatic support stocking of FIG. 8.

FIG. 12 is a rear view of the therapeutic pneumatic support stocking of FIG. 8.

FIG. 13 is a top view of the therapeutic pneumatic support stocking of FIG. 8; and,

FIG. 14 is a bottom view of the therapeutic pneumatic support stocking of FIG. 8.

Portions of FIGS. 1 through 14 are shown in broken lines illustrating portions of the article and environmental subject matter that form no part of the claimed design.

1 Claim, 14 Drawing Sheets
